UNITED STATES PATENT OFFICE.

JOSEPH FASKE, OF CINCINNATI, OHIO, ASSIGNOR TO THE NATIONAL HARDWARE COMPANY, OF SAME PLACE.

SPRING-GEAR FOR VEHICLES.

SPECIFICATION forming part of Letters Patent No. 475,304, dated May 24, 1892.

Application filed January 2, 1892. Serial No. 418,905. (No model.)

To all whom it may concern:

Be it known that I, JOSEPH FASKE, a citizen of the United States, and a resident of Cincinnati, in the county of Hamilton and State of Ohio, have invented certain new and useful Improvements in Spring-Gears for Vehicles, of which the following is a specification.

The object of my invention is to provide an inexpensive and reliable device for coupling the vehicle-body to the gear, particularly to the rear axle and head-block.

The invention consists in the peculiar combination and arrangement of parts illustrated in the accompanying drawings, in connection with which it will be first fully described, and will then be particularly referred to and pointed out in the claims.

Referring to the drawings, in which like parts are indicated by similar reference-letters wherever they occur throughout the various views, Figure 1 is a longitudinal central vertical sectional view of a buggy body and gear, the wheels being omitted, embodying my invention. Fig. 2 is an inverted plan view of the same with the front axle removed. Fig. 3 is a detail view, in vertical section, of the spring and its coupling upon an enlarged scale. Fig. 4 is an edge and Fig. 5 is a side elevation of one of the boxes for coupling the body to the gear. These views are also upon an enlarged scale.

The body A, side bars B, rear axle C, front axle C', and head-block D are all of ordinary construction and substantially the same as now used upon side-bar buggies.

E E' are two U-shaped bars or rods, the ends of which are formed in perforated bosses to receive bolts of swinging shackles e, to which they are rigidly coupled to the rear axle and front head-block, respectively. The transverse portions e' of the rods E E' extend entirely across the bottom of the body, the bends forming the arms being outside of the body sides, so that the body may pass down between the arms without striking them. The bars E E' are journaled in boxes F, which are secured to the side sills a of the body. These boxes are preferably made in a single

piece, and the bars E E' are passed through them before they are bent or the shackle-eyes are formed. Upon the outer edges of the boxes are formed projecting lugs f, which, when the boxes are secured to the bars a of the body, bear lightly against the longitudinal arms of the bars E E' and prevent side motion of the body. The center part of the transverse portions of the bars E E' are formed square or angular, as seen in Fig. 3, to fit a square perforation in the couplings G. These couplings have each a perforated web g for bolts g', which secure the couplings rigidly to the ends of an upwardly-arched steel spring H. The spring thus connects the transverse portions of the bars E E'. Now it will be seen that any weight in the body which depresses it is resisted by the spring H, the tendency being to bend the ends of the spring around the inner ends of the couplings G. The strength of the spring determines the weight the body will sustain. The bars and spring are compelled to act in unison, so that a weight in any part of the body will depress it about equally at all points. All uneven movements or rocking of the body when in use is therefore prevented.

To prevent lateral movement of the coupling-boxes G upon the bars E E', I cut a transverse groove e² across the top of the square portion and countersink the top of the coupling to tighten the metal over the groove in the bar. Then by a punch I force a portion of the metal of the coupling into the groove in the bar, as seen at g', Fig. 3.

What I claim, and desire to secure by Letters Patent, is—

1. The combination, substantially as hereinbefore set forth, with the body and gear, of the U-shaped bars E E', shackled, respectively, to the rear axle and head-block, the boxes coupling the transverse portions of said bars to the body, the coupling G, rigidly secured upon the bars, and the arched spring H, having its opposite ends secured rigidly to the couplings.

2. The combination, with the body and gear, of the U-shaped bars shackled to the rear

axle and head-block, the boxes F for coupling the bars to the body and having projections f bear against the arms of said bars and prevent lateral motion of the body, the couplings 5 G, rigidly secured to the central transverse portions of the coupling-bars, and the arched flat spring H, secured at its ends to the

couplings G, substantially as shown and described.

JOSEPH FASKE.
